UNITED STATES PATENT OFFICE.

JOHN SCHUMACHER, OF LOS ANGELES, CALIFORNIA.

REENFORCED-COVERED-EDGE PLASTER BOARD.

Application filed November 9, 1925. Serial No. 67,912.

This invention relates to plaster board and especially means for reenforcing the edges thereof. Plaster board is subjected to comparatively rough usage during manufacture, transportation, and installation. Edges thereof unless protected are liable to chipping, cracking and other damage which mars the board so that the production of smooth joints between panels becomes difficult and even starts peeling of the cover sheets from the plaster body.

The present invention relates to a plaster board having an edge covered by a sheet of pliable material, the sheet being arranged to reenforce the edge and to provide recesses for the lodgment of plaster putty and the like for filling joints. These objects together with other objects and corresponding accomplishments are obtained by means of the embodiment of my invention illustrated in the accompanying drawing, in which:

Fig. 1 is a perspective view of a plaster board panel constructed in accordance with my invention; Fig. 2 is a horizontal section through a panel; and Fig. 3 is a transverse vertical section through a panel showing a fragment of an adjacent panel with the joints covered by paper tape.

Referring more particularly to the drawing, 5 indicates a core of cementitious material such as gypsum plaster, composition thereof, or like material well known in the art. The body has its faces covered by sheets of paper or the like indicated by 6 and 7. These sheets are bound to the plaster body in a manner well known in the art. It is the common practice to provide such structures with exposed edges between the cover sheets. In the present construction, I have covered these edges with strips of paper or like material indicated by 7. The strips 7 are corrugated transversely, as best shown in Fig. 2. Whereas I have shown independent strips of edge covering material, it is obvious that the cover sheets may be made longer than the panel, corrugated or

fluted at the edges and turned over providing a corner. With the construction shown herein, the marginal edges of the face sheet may be bevelled as indicated by 8.

In Fig. 3 I have indicated adjacent panels of plaster board A and B. The marginal edges of the board are bevelled so that the abutting panels have recesses at the joints with sloping walls. The crack between the panels may be filled with plaster, putty or cement. The corrugated edge provides valleys extending transversely, in which the plaster cement may lodge and become anchored, thereby holding the panel against axial displacement. Bevelled paper tape C may be placed over the joint and cemented to the cover sheet, thereby providing a flush surface for the panel at the joint. The result is a finished structure which is stable. The plaster board itself is strong, the edge being protected and reenforced by the protective covering.

What I claim is:

1. A plaster board having a protective edge covering of paper or the like bonded thereto, said covering being fluted with the ridges and dales extending transversely of the edge of the board.

2. A plaster board having a cementitious body and protective edge covering of paper or the like bonded thereto, said covering being corrugated with the ridges and dales extending transversely of the edge of the board.

3. A plaster board having a cementitious body, cover sheets for the faces thereof bonded thereto, the edges of said board being covered by strips of paper corrugated with the ridges and dales extending transversely of the edge of the board and bonded thereto.

In witness that I claim the foregoing I have hereunto subscribed my name this 27th day of October, 1925.

JOHN SCHUMACHER.
